UNITED STATES PATENT OFFICE.

GEORGE F. NEWELL, OF GREENFIELD, MASSACHUSETTS.

SEWING-MACHINE.

SPECIFICATION forming part of Letters Patent No. 253,222, dated February 7, 1882.

Application filed February 26, 1881. (No model.)

To all whom it may concern:

Be it known that I, GEORGE F. NEWELL, of Greenfield, in the county of Franklin and Commonwealth of Massachusetts, have invented 5 a new and useful Improvement in the "Take-up" of Sewing-Machines, of which the following is a true and full specification.

My invention relates to that device in the sewing-machine by which the thread, after the 10 stitch is made, is taken up or released so that a slack is made and held ready for the next descent of the needle. Some contrivance of this kind, as is well known, is necessary for this purpose on all machines, and is known as the 15 "take-up;" but in many of them there is a difficulty of slackening the thread too much, or of drawing it too tight, or not allowing time enough, of allowing the thread to kink, and they are often noisy and complicated. My in- 20 vention is intended to obviate these objections.

In the accompanying drawings, Figure 1 is a front elevation of the face-plate. Fig. 2 is a side elevation of the same.

Similar reference-letters indicate like parts 25 in both figures.

Referring to the drawings, A is the face-plate of the machine.

B is the needle-bar, perforated at its upper end at a'.

30 C is the loop on a cross-bar on one side of the needle-bar, and D is a loop on the other side of said needle-bar.

E is a loop on the needle-bar.

F is a bar extending across the front of the 35 face-plate, midway between the upper and lower edges of the same.

The thread, as it comes from the spool and under the tension, passes as usual through a hole in the upper end of the needle-bar and 40 down about half the length of the face-plate.

A, at which point a bar, F, extends across the front of the face-plate, projecting a little for-

ward of the needle-bar B. On one side of this bar F and close to the needle-bar is fastened a loop, C, or "thread-eye," as it is called. On 45 the needle-bar is a similar loop, E, and another loop, D, fastened to the cross-bar on the other side of the needle-bar and corresponding to the loop C; and these form the take-up. The thread, coming down through the upper end of 50 the needle-bar, is first passed through the loop C, then up and through the loop E on the needle-bar, then down again through loop D to the eye of the needle. In the drawings the needle-bar is represented as being on its last 55 half of the upward movement, and the thread is all taut. Now, as it (said bar) descends and drives the needle through the cloth it releases thread enough from the upper end of the needle-bar to form the loop for the shuttle, 60 and on the lower half of this downward motion the take-up takes up the same amount of thread that it slackened on the first half of the movement. On the first half of the upward movement of the needle the take-up relieves 65 the same amount of thread that is taken up by the needle-bar, thus allowing the proper amount of thread to the shuttle. At this point, the shuttle having passed the needle, the take-up and the needle-bar, working in unison, take up 70 the thread and form the stitch.

I claim—

The face-plate of a sewing-machine, provided with a broken or slotted cross-bar, F, having loops C D, placed thereon at opposite points, 75 in combination with a needle-bar playing vertically in said slot, provided with a simple loop, E, substantially as and for the purpose set forth.

GEO. F. NEWELL.
